REFRIGERATOR CONSTRUCTION

Russell T. Smith, Greenville, Mich., assignor to
 Gibson Refrigerator Company, Greenville,
 Mich., a corporation of Michigan

Application March 16, 1931. Serial No. 522,797

4 Claims. (Cl. 62—116)

This invention relates to refrigerator constructions and more particularly to constructions especially adapted for household or domestic refrigerators.

5 An object of this invention is a construction employing a motor-compressor-fan unit, and an air cooled condenser, all enclosed within a buffet top casing or cover provided with a suitable air inlet and an outlet. In the preferred embodiment of the invention the condenser forms a shield or screen for the motor-compressor-fan unit, and an auxiliary or second casing forms an enclosure for the motor-compressor-fan unit per se, the condenser being exposed within the 15 prime casing.

Still further objects will readily occur to those skilled in the art upon reference to the following description and the accompanying drawings in which

20 Fig. 1 is a top view, as if in section on line 1—1 of Fig. 2.

Fig. 2 is a rear view, as if in section on line 2—2 of Fig. 1.

Fig. 3 is a side view, as if in section on line 25 3—3 of Fig. 1.

Referring to the drawings, it will be seen that the construction includes a cabinet 10 having a top wall 12 and a mounting board 14, there being a buffet top or casing 16 forming a cover.

30 Supported on and secured to the mounting board is a motor-compressor-fan unit including a motor 20, a compressor 22, and a fan 24, all having the common shaft 26. A condenser 28, comprising a vertical row of end-connected 35 pipes, is also supported on the board 14, its plane being substantially parallel to the fan shaft 26 and substantially perpendicular to the top wall of the cabinet. The condenser partitions the casing 16 into an operating compartment and 40 an air compartment, as can be seen readily.

Disposed within the casing 16 is a second casing or enclosure having a top wall 36, end walls 38 and 39, and a side wall 40. One of the end walls 38, is apertured, as at 42, and the blades of 45 the fan are disposed within the aperture, so as to form thereof, an outlet port thru which the fan may discharge. The enclosure or second casing, further, is so disposed within the casing 16 that the free edge of its top wall is adjacent 50 the uppermost pipe of the condenser, the latter thus forming, in effect, another side wall of the enclosure.

On the rear wall of the cabinet are two sheet metal channels or tubes 50 and 52, one of which, 55 50, forms the air inlet for the construction, the

other of which, 52, forms the air outlet. The inlet 50 extends down to near the base of the cabinet, and its upper end is closed, and is disposed immediately above the air inlet opening 54 of the casing 16. The outlet 52 also extends 60 downwardly, tho not so far as does the inlet 50, and its upper end is closed at 56, and is disposed immediately above an opening 58 in the casing 16, this last opening being aligned 65 with the opening 42 of the enclosure.

When the fan is operating, cool air is drawn up thru the inlet 50, and opening 54 into the casing 16. It is then drawn thru the condenser, extracting heat therefrom, and passes into the enclosure, being forced out of the latter by the 70 fan 24 which discharges thru openings 42 and 58, and outlet tube 52.

Now having described the invention and the preferred embodiment thereof, it is to be understood that the said invention is to be limited, 75 not to the specific details herein set forth, but only by the scope of the claims which follow.

What I claim is:

1. In combination with a refrigerator cabinet 80 having a motor-compressor-fan unit on the top wall thereof, a condenser also on the top wall of the cabinet and comprising pipes in a vertical row whose plane is substantially parallel to the axis of the fan and substantially perpendicular to the wall, a casing surrounding and covering the unit and the condenser and having an air inlet on its rear wall and on that side of the condenser remote from the unit, and having an air outlet on its rear wall near the discharge path of the fan, a relatively long conduit 90 for leading air to said inlet and a relatively short conduit for leading air from said outlet.

2. In combination with a refrigerator cabinet 95 having a motor-compressor-fan unit on the top wall thereof, a condenser also on the top wall of the cabinet and comprising pipes in a vertical row whose plane is substantially parallel to the axis of the fan and substantially perpendicular to the wall, a casing surrounding and covering the unit and the condenser and having an air inlet on its rear wall and on that side of the condenser remote from the unit, and having an air outlet on its rear wall near the discharge path of the fan, said condenser serving 100 as a barrier between the air inlet and the fan and as a shield for the latter, a relatively long conduit for leading air to said inlet and a relatively short conduit for leading air from said outlet.

105 3. In combination with a refrigerator cabinet 110 having a motor-compressor-fan unit on the top wall thereof, a condenser also on the top wall of the cabinet and comprising pipes in a vertical row whose plane is substantially parallel to the axis of the fan and substantially perpendicular to the wall, a casing surrounding and covering the unit and the condenser and having an air inlet on its rear wall and on that side of the condenser remote from the unit, and having an air outlet on its rear wall near the discharge path of the fan, said condenser serving as a barrier between the air inlet and the fan and as a shield for the latter, a relatively long conduit for leading air to said inlet and a relatively short conduit for leading air from said outlet.

110

having a motor-compressor-fan unit on the top wall thereof, a condenser also on the top wall of the cabinet and comprising pipes in a vertical row whose plane is substantially parallel to the axis of the fan and substantially perpendicular to the wall, a casing surrounding and covering the unit and the condenser and having an air inlet on its rear wall and on that side of the condenser remote from the unit, and having an air outlet on its rear wall near the discharge path of the fan, the air inlet comprising a tube on the rear wall of the cabinet and whose lower end is near the base of the cabinet.

4. In combination with a refrigerator cabinet having a motor-compressor-fan unit on the top

wall thereof, a condenser also on the top wall of the cabinet and comprising pipes in a vertical row whose plane is substantially parallel to the axis of the fan and substantially perpendicular to the wall, a casing surrounding and covering the unit and the condenser and having an air inlet on its rear wall and on that side of the condenser remote from the unit, and having an air outlet on its rear wall near the discharge path of the fan, the air inlet comprising a tube on the rear wall of the cabinet and whose lower end is near the base of the cabinet, the air outlet comprising a tube on the rear wall of the cabinet.
